UNITED STATES PATENT OFFICE.

ARTHUR TALBOT CAMPBELL, OF SEATTLE, WASHINGTON, ASSIGNOR TO BAND-BOUND BOX COMPANY, OF SEATTLE, WASHINGTON, A CORPORATION OF WASHINGTON.

BOX-BLANK FOLDING AND FASTENING MACHINE.

Application filed September 30, 1926. Serial No. 138,614

This invention relates to machines for inserting fastening devices, and more particularly to machines for inserting nails in boxes, thereby to hold the box parts in assembled relation.

Generally stated, the object of the invention is to provide a novel and improved construction of machine for inserting fastening devices rapidly and satisfactorily in the desired manner, under the full control of the operator or attendant.

More specifically stated, the object of the invention is to provide a machine having means for accomplishing more or less of the folding and assembling operation, necessary as a preliminary to the insertion of fastening devices to hold the box parts in assembled relation.

It is also an object to provide certain details and features of construction, and combinations tending to increase the general efficiency and the desirability of a fastener-inserting machine of this particular character.

To these and other useful ends, the invention consists in the matters hereinafter set forth and claimed, and shown in the accompanying drawings, in which,—

Fig. 1 is a front elevation of a fastener-inserting machine involving the principles of the invention, showing certain portions in vertical section, and showing some portions broken away, for convenience of illustration.

Fig. 2 is a vertical section on line 2—2 in Fig. 1.

Fig. 3 is an enlarged, horizontal section on line 3—3 in Fig. 1.

Fig. 4 is a plan view of certain parts shown in Fig. 3, showing said parts in a different position.

Fig. 5 is a horizontal section on line 5—5 in Fig. 1.

Fig. 6 is a perspective of a portion of a box, in partially assembled condition, showing the parts ready to be operated on by the folding and assembling instrumentalities of the machine.

Fig. 7 is a similar view, showing said parts brought together, and showing the nails inserted to hold the parts in assembled relation.

Fig. 8 is a detail section on line 8—8 in

Fig. 7, showing certain portions broken away for convenience of illustration.

Fig. 9 is a perspective of the finished box.

As thus illustrated, the invention comprises 55 a machine body 1 having a table 2 at the front thereof, at the proper height for the convenient placing of the box parts thereon by the operator or attendant. The box to be made comprises the side sections 3 and 4, 60 and the bottom section 5, together with end walls 6 and cleats 7, 8, 9 and 10, these cleats being duplicated at each end of the box. Metal strips 11 are applied to the three sections of the blank, to flexibly connect them 65 together, and the cleats 8 and 10 are all grooved at 12 to receive the end walls 6, as shown. The top and bottom cleats 10 and 8 have notches or grooves 13, and the vertical cleats 7 and 9 have tongues 14 in their upper and lower ends to receive said tongues.

Therefore, when the box parts are assembled, as in Fig. 6, on the table 2, it will be seen that the cleats 7 and 9 will occupy positions at the left and right of the raised portion 15 of said table, while the cleat 8 will be in position at the outer edge of this raised portion, as shown at dotted lines in Fig. 3 of the drawings. The head or end wall 6 will rest on the raised portion 15 of the table, and the cleat 10 will be in position as shown on said table, so that the positions of the parts are as shown in Fig. 6 of the drawings. It remains now to fold the sides 3 and 4 toward each other, and to move the cleat 10 into 80 engagement with the end wall 6, and into engagement with the ends of the cleats 7 and 9, so that the parts will then occupy the position shown in Fig. 7 of the drawings.

For this purpose, therefore, two horizontal 90 and parallel and longitudinally arranged shafts 16 are provided on the machine, mounted in suitable bearings thereon, and provided with cams 17 to engage the side sections 3 and 4, to press the latter toward each other. Said shafts are also provided with cam-like 95 portions 18 to engage the bottom section 5 of the box, to hold the box against outward displacement, as shown in Fig. 4 of the drawings. Presser arms 19 are pivoted at 20 on 100 the machine, to swing about vertically disposed axes, these arms being held in normal

position by the springs 21, as shown in Fig. 3 of the drawings. These arms have rollers 22 at their other ends, and the shafts 16 have cams 23 formed to engage said rollers, whereby at the proper time, by properly timing the action of the different parts, the arms 19 press the cleat 10 into position, as shown in Fig. 4 of the drawings, preliminary to the driving of the nails 24 by which the box parts are held in assembled relation. One shaft 16 and its allotted arm 19 are slidably laterally by means of a hand adjusting screw 25, in any suitable or desired manner, and one of the two bars 26 forming part of said table, 15 and forming the supports for the cleats 7 and 9, is adjustable in unison with said shaft and presser arm, whereby boxes of different widths or sizes may be made.

The shaft 16 may be rotated by any suitable or desired mechanism, and may be controlled in any suitable or desired manner. However, a simple and effective arrangement for this purpose comprises the sprocket chains 27 and 28 on the sprocket wheels 29 and 30 at 20 the rear ends of said shafts. These sprocket chains are operated by the sprockets 31 and 32 on the shafts 33 and 34 below, the power communicated through said sprocket chains being controlled by a suitable clutch, through 25 the medium of the foot treadle 36, of any suitable character, the two shafts 33 and 34 being operated by power communicated thereto from the power shaft 37, through the gearing 38, as shown.

For the driving of the nails 24, any suitable nailing mechanism can be employed, the nailing mechanism 39 being of any suitable or desired character. However, it is desirable that the operation of said nailing mechanism shall be automatic, and for this purpose a trip bar 40 is disposed transversely of the machine, as shown in Fig. 3 of the drawings, in position to be operated up and down by the cams 41 on the shafts 16 previously mentioned. This trip bar carries a vertically disposed rod 42 that controls the clutch device 43 on the shaft 33 below, which shaft is connected to the reciprocating element 44 of the nailing mechanism by the pitman 45 that extends downwardly to the crank 46 on the shaft 33 previously mentioned. Thus, at the proper time, the trip bar 41 is actuated upward, by the cams 41, to trip the clutch 43, and to thereby cause the operation of the nailing mechanism to insert the nails. The cams 41 are rigid with the cams 23 previously mentioned, and are slidable on the shaft 16, being held in normal position by the springs 47, shown in Fig. 3 of the drawings. Therefore, 50 if the cleat 10 catches on something, and does not slide into position, the arms 19 are not operated, inasmuch as the springs 47 will yield and permit the cams 23 and 41 to slide backward on the shaft 16, this displacement 55 of the cams being caused by the cam engage-

ment between the cams 23 and the rollers 22, thereby backing the cams 41 outward from under the bar 40, and preventing the latter being operated to start the nailing mechanism. Consequently, in any such case, when 70 the cleat 10 is not pushed into proper position, the nailing mechanism is automatically prevented from operating, and no nails are driven, and the operator or attendant can then rearrange the parts and start the machine again.

As stated, the nailing mechanism may be of any suitable or desired character, and such mechanism may be adapted to drive fastening devices of any suitable or desired character, but, as shown, the mechanism is of that common and well known kind in which the nails are carried on a shaker box 48, which is moved up and down in the customary manner by a pitman 49 connected to the crank 50, 80 which is operated from the power connections below through the sprocket chains 51 and 52, in a manner that will be readily understood. The nails are automatically fed downward through tubes 53 to the mechanism 39, and 90 are inserted by the drivers 54 carried by the reciprocating head 44 in the customary manner.

It will be seen, therefore, that a machine constructed in accordance with the invention, the drawings being illustrative of one form of the invention, is capable of not only inserting fastening devices, to hold the parts in assembled relation, but is also capable of performing more or less of the folding and assembling operation, necessary to bring the parts into proper relation to each other, preliminary to the insertion of the nails or other fastening devices. In the form of the invention shown and described, the operator or attendant will bend or fold the three-section blank into about the condition shown in Fig. 6 of the drawings, and will place the head or end wall 6 and the cleat 10 in position, as shown, but it will be understood that the machine may perform any amount of folding and assembling, or may do more or less of the folding and assembling, without departing from the spirit of the invention, the invention providing for the first time means for engaging and relatively folding the sections of a metal-bound box-blank, and means for bringing the box parts into proper assembled relation to receive fastening devices to hold the parts in the relation required for the finished box.

With further respect to the adjustability of the machine, for boxes of different sizes, it will be seen that the shafts 16 carry spacers 55 which can be shifted around on said shafts to vary the position of the cams 18 thereon, so that these cams are in effect adjustable longitudinally of the two shafts for boxes of different depths. For boxes of different depths, 125 the table formed by the members 26 is adapted 130

to slide in and out, or to slide endwise, so that the position of the outer end of this table may be varied in accordance with the position of the cams 18 for boxes of different depths.

5. What I claim as my invention is:

1. In machinery for folding and assembling box parts together, preliminary to the insertion of fastening devices to hold the parts in box form, the combination of means for supporting the parts in position to be completely folded and assembled by the machinery, rotary means for engaging the sides of the box to fold them toward each other, having parallel axes of rotation, with rotation about each axis in one direction only, but with the direction of rotation about one axis opposite to that of the other, and instrumentalities for causing the operation of said means.

2. A structure as specified in claim 1, in combination with mechanism to insert fastening devices inwardly through interlocking parts of the box to hold the side walls in proper relation to each other for the finished box.

3. A structure as specified in claim 1, in combination with a device to push the upper cleat of the box into engagement with the cleats of the sides of the box, and means to automatically control said device.

35. 4. A structure as specified in claim 1, in combination with a device to push the upper cleat of the box into engagement with the cleats of the side walls, and mechanism automatically controlled to insert nails through the interlocking ends of the top cleat and the side cleats, after said folding and assembling operation has brought the parts into final relation to each other.

40. 5. A structure as specified in claim 1, comprising mechanism to insert nails inwardly through certain interlocking parts of the folded and assembled box, and means to automatically control said nailing mechanism.

45. 6. A structure as specified in claim 1, said folding means comprising horizontally disposed shafts provided with cams for engaging the side walls of the box, said cams shaped to press the side walls toward each other.

50. 7. A structure as specified in claim 1, said folding means comprising horizontally disposed shafts provided with cams for engaging the side walls of the box, said cams shaped to press the side walls toward each other, presser arms to move the top cleat into engagement with the cleats of the side walls of the box, cams on said shafts to operate said presser arms, a nailing mechanism to insert nails through the interlocking ends of the top cleats and the side cleats, instrumentalities including a trip bar to automatically control said nailing mechanism, and cams on said shafts to operate said trip bar, said presser-arm cams and trip-bar cams being slidable on said shafts, and being spring held in operative position, whereby these slidable cams are mov-

able on said shafts if the movement of the presser arms is obstructed, whereby to move the trip-bar cams out of operative relation to the trip bar, whereby to automatically prevent operation of the nailing mechanism in case the top cleat catches on something and is not pushed into position to receive the nails.

8. In machinery for folding a flexible box blank, the combination of means in position to engage the sections of the blank, operative to automatically fold the side walls of the blank toward each other, relatively to the bottom section of the blank, requiring a partial preliminary folding of the blank by hand to permit insertion thereof in the machine, and instrumentalities for causing the operation of said means, together with supporting means to support the partially folded box blank in position for said automatic folding operation.

9. A structure as specified in claim 8, in combination with mechanism to insert fastening devices through certain parts of the fully folded blank to hold it in folded condition.

10. A structure as specified in claim 8, in combination with instrumentalities for supporting other parts of the box, and devices for moving these other parts into proper relation to said folded box-blank sections, together with means for inserting fastening devices to hold said blanks and other box parts in assembled relation.

11. In machinery for folding and assembling box parts together, preliminary to the insertion of fastening devices to hold the parts in box form, the combination of means for supporting the parts in position to be folded and assembled, means for engaging the sides of the box to fold them toward each other, and instrumentalities for causing the operation of said means, in combination with a device to push the upper cleat of the box into engagement with the cleats of the sides of the box, and means to automatically control said device.

12. In machinery for folding and assembling box parts together, preliminary to the insertion of fastening devices to hold the parts in box form, the combination of means for supporting the parts in position to be folded and assembled, means for engaging the sides of the box to fold them toward each other, and instrumentalities for causing the operation of said means, in combination with a device to push the upper cleat of the box into engagement with the cleats of the side walls, and mechanism automatically controlled to insert nails through the interlocking ends of the top cleat and the side cleats, after said folding and assembling operation has brought the parts into final relation to each other.

13. In machinery for folding and assembling box parts together, preliminary to the insertion of fastening devices to hold the parts in box form, the combination of means

for supporting the parts in position to be folded and assembled, means for engaging the sides of the box to fold them toward each other, and instrumentalities for causing the operation of said means, said folding means comprising horizontally disposed shafts provided with cams for engaging the side walls of the box, said cams shaped to press the side walls toward each other.

10 14. In machinery for folding and assembling box parts together, preliminary to the insertion of fastening devices to hold the parts in box form, the combination of means for supporting the parts in position to be folded 15 and assembled, means for engaging the sides of the box to fold them toward each other, and instrumentalities for causing the operation of said means, said folding means comprising horizontally disposed shafts provided with 20 cams for engaging the side walls of the box, said cams shaped to press the side walls toward each other, presser arms to move the top cleat into engagement with the cleats of the side walls of the box, cams on said shafts 25 to operate said presser arms, a nailing mechanism to insert nails through the interlocking ends of the top cleats and the side cleats, instrumentalities including a trip bar to automatically control said nailing mechanism, and 30 cams on said shafts to operate said trip bar,

said presser-arm cams and trip-bar cams being 35 slideable on said shafts, and being spring held in operative position, whereby these slideable cams are movable on said shafts if the movement of the presser arms is obstructed, whereby to move the trip-bar cams out of operative relation to the trip bar, whereby to automatically prevent operation of the nailing mechanism in case the top cleat catches on something and is not pushed into position to 40 receive the nails.

15. In machinery for folding a flexible box blank, the combination of means in position to engage the sections of the blank, operative to automatically fold the side walls of the 45 blank toward each other, relatively to the bottom section of the blank, and instrumentalities for causing the operation of said means, together with supporting means to support the partially folded box blank in position for said automatic folding operation, and for supporting other parts of the box, and devices for automatically moving these other parts horizontally into proper relation to said 50 box-blank sections, together with means for inserting fastening devices to hold said blank and other box parts in assembled relation.

Specification signed this 8th day of Sept., 1926.

ARTHUR TALBOT CAMPBELL.
